UNITED STATES PATENT OFFICE.

CHARLES SPAETH, OF CLEVELAND, OHIO, ASSIGNOR TO THE MARVEL EQUIPMENT COMPANY, OF CLEVELAND, OHIO, A CORPORATION OF OHIO.

DISPENSING AND MEASURING PUMP.

Application filed October 10, 1922. Serial No. 593,556.

To all whom it may concern:

Be it known that I, CHARLES SPAETH, a citizen of the United States, residing at Cleveland, in the county of Cuyahoga and State of Ohio, have invented certain new and useful Improvements in a Dispensing and Measuring Pump, of which the following is a specification.

This invention relates to a dispensing and measuring pump of the type which connects with and is mounted upon the head of a barrel or drum and provided with an intake pipe extending into the barrel. These pumps are especially designed for attachment and use with the steel barrels or drums commonly employed to ship and store oil and grease, and the present pump is particularly constructed to permit a quick and convenient attachment and an operative connection to be made with barrels and drums of different sizes and capacities. In this connection it should be understood that the barrels and drums in use vary considerably in height and diameter and that to make an operative connection capable of permitting all of the contents to be withdrawn it is necessary that the intake end of the pipe for the pump be located at the extreme bottom of the barrel. It is also advantageous to have the pump body mounted in a stable manner upon the head of the barrel and not on the intake pipe itself, and to serve such useful ends and purposes I have constructed the pump in a particular way, all as hereinafter shown and described and more concisely pointed out in the claims.

In the annexed drawings, Fig. 1 is a side elevation of my improved pump attached to a steel barrel of small size, the barrel being in section and part thereof being broken away. Fig. 2 is a side elevation and sectional view of the same pump attached to a much larger steel barrel and showing the intake pipe extended its full length and resting upon the bottom of the barrel. Fig. 3 is an enlarged vertical section of the pump and barrel, the barrel and the pump intake pipe being broken away and foreshortened to permit the bottom portion of the barrel to be shown on the sheet.

A general practice at the present time is to ship and store oil and grease in barrels or drums made either of wood or metal, but more commonly the latter, for example a barrel 2 such as shown in the drawings. A

screw-threaded bung opening 3 of standard size is provided in the head 4 whether the barrel be large or small. Into this bung opening I screw a tubular fitting or coupling member 5 which is provided with a reduced screw-threaded extremity 6 for that purpose. The upper end of coupling member 5 has a relatively long and smooth bore 7 and a boss 8 at one side of this bore. The pump base 9 has a shouldered bottom face 65 10 adapted to seat upon the flat top of member 5, and also a reduced round extension 11 adapted to extend into bore 7 and fit tightly therein, a set screw 12 being extended through boss 8 to secure the parts together. The chambered middle portion of coupling member 5 is also provided at one side with a boss 13 adapted to receive a short horizontal drain pipe 14 which connects with and supports an overflow or drain pan 15 directly 70 above the head of the barrel, although the coupling member may be rotated to place the pan over or beyond the chime of the barrel if necessary or desired. Pan 15 has a vertical border flange 16 and a dished or sloping bottom 17, and the receptacle or container C which is to receive the oil is adapted 75 to be seated upon raised ribs 18 within this pan, see Fig. 3. Oil dripping or overflowing into the pan passes through the bottom channel 19 and out of pipe 14 into the chamber within coupling member 5. The bottom end of member 5 is open to permit the oil to escape into the barrel, notwithstanding that an intake pipe 20 for pump P extends 80 upwardly into member 5 and connects with the tubular extension 11 of pump base 9. Pipe 20 is relatively long but of less length than the smaller sizes of barrels in general use. An extension sleeve or tube 21 is therefore slidably fitted over the lower end of pipe 20, and the bottom end of the pipe is flanged outwardly at 22 to engage an inner shoulder 23 within the upper end portion of the sleeve or tube 21 so as to secure these 85 parts together and limit the telescopic movement outwardly of tube 21. A screw-threaded ring or gland 24 is sleeved on pipe 20 and screwed into the upper end of extension tube 21 to compress the packing 25 and 90 maintain a tight joint around the slidable joint, as otherwise a leak at this point might interfere with the functioning of the pump, especially when the liquid level in the barrel falls below the upper end of extension tube 110

20 and exposes the joint to atmospheric pressure, a vent passage being open through drain pipe 14. The bottom end edge of extension tube 20 is notched or scalloped to permit the oil to enter the tube when at rest upon the bottom head 26 of the barrel, and if the barrel is a small one or relatively short in length the extension tube 21 is telescoped more or less over pipe 20 as shown in Fig. 1. This setting or relationship of parts occurs when coupling member 5 is screwed into the bung-opening or the pump is entered and secured within the coupling member, and in the case of a larger barrel the extension tube 21 adjusts itself or is self-regulable to the length of the barrel assuming that it is extended to its limit when just introduced into the barrel. The lower portion of the intake pipe is reduced in diameter which provides a stop shoulder 20' to limit the upward movement of tube 21, and the flanged end 22 limits the downward movement thereof. Tube 21 is also smaller in diameter than the coupling end 6 of member 5 to permit it to pass through the opening in the head of the barrel.

Pump P may be constructed in various ways, but as shown the base 9 thereof has a flanged enlargement adapted to seat the cylinder 27, and a suitable valve 28 controls the intake port 29 in this base. A valved piston or plunger 30 is adapted to be reciprocated within the cylinder by means of a pinion 31 journaled in the dome-shaped head 32 of the pump, and a crank handle 33 is affixed to the exposed end of the pinion shaft 34 to rotate the pinion and operate the plunger rod 35 which is provided with rack teeth at one side meshing with the teeth of the pinion. Plunger 34 extends through the top of head 32 and is guided thereby, but inasmuch as the rack teeth permit escape of the oil at this point the rod is encased by a tube 35 which is closed at its top by a cap 37. The bottom end of this tube is screwed into the upper side of the head and it is of larger diameter internally than the outer diameter of the plunger rod

so that a chamber is provided to receive and hold oil during the operation of the pump. A goose-neck discharge spout 38 is connected with one side of head 32, and the discharge end of this spout is located at a higher elevation than the head directly above the drain pan. A screw 39 extends through cap 37 to regulate within limits the stroke of the plunger and the amount of liquid to be delivered.

What I claim, is:

1. A dispensing and measuring pump having a tubular base provided with a reduced integral extension, a separate hollow coupling member adapted to receive said extension having an open screw-threaded reduced portion adapted to be inserted and secured tightly within an opening in the head of a barrel, a drain pipe connected with the side of said separate coupling member, a set screw at one side of said coupling member adapted to engage said pump base extension, a pipe extending through said coupling member and connected with said pump base extension, and an extensible inlet tube slidably sleeved upon said pipe adapted to permit said pump to be used with barrels of different sizes and capacities.

2. A dispensing and measuring pump having a base provided with a round smooth extension, a hollow coupling member having a smooth bore at its upper end adapted to receive said extension and a reduced lower end which is screw-threaded to fit within a screw-threaded opening in a barrel, a drain pan having a lateral drain pipe connected with said hollow coupling member, an intake pipe for the pump extending through said coupling member and connected with said pump base, a tubular extension slidably mounted upon the lower end of said intake pipe, and spaced stops on said pipe limiting the slideable movement of said tubular extension thereon.

In testimony whereof I affix my signature hereto.

CHARLES SPAETH.
